(57) **ABSTRACT**

In a thread standing device capable of switching a plurality of spool pins between a stored state and a deployed state and a sewing machine having the thread standing device, an operability is improved during the switching operation. In a thread standing device, a plurality of spool pins can be switched between a stored state and a deployed state, operation portions related to a switching operation of the plurality of spool pins is provided, and the plurality of spool pins are configured to be switched from the stored state to the deployed state when the operation portions are operated.

THREAD STANDING DEVICE AND SEWING MACHINE

CROSS-REFERENCES TO RELATED APPLICATIONS

This patent specification is based on Japanese patent application, No. 2021-128999 filed on Aug. 5, 2021 in the Japan Patent Office, the entire contents of which are incorporated by reference herein.

BACKGROUND OF THE INVENTION

1. Field of the Invention

The present invention relates to a thread standing device and a sewing machine having the thread standing device.

2. Description of the Related Art

In a lock stitch sewing machine, seams are formed by entangling an upper thread with a lower thread. The upper thread is wound around a thread reel and the thread reel is placed on a spool pin provided on a thread standing device of the sewing machine.

Conventionally, a thread standing device having a plurality of spool pins is known. In such a thread standing device, the sewing can be performed using a plurality of upper threads and an upper thread for replacement can be preliminarily placed. In addition, a thread standing device capable of storing the spool pins is proposed to downsize the sewing machine during storage. For example, Patent Document 1 shows a thread standing device having a plurality of spool pins attachable to an upper lid of the sewing machine. In the above described thread standing device, the spool pins can be stored so that the upper lid can be closed during the storage of the sewing machine.

[Patent Document 1] Japanese Unexamined Patent Application Publication No. 2019-208548

BRIEF SUMMARY OF THE INVENTION

In the thread standing device of Patent Document 1, in order to switch the spool pins from a stored state to a usage state (deployed state) where the thread reels can be placed on the spool pins, an operator should pull up each of a plurality of spool pins. Thus, there is a room for improvement in operability.

The present invention provides a thread standing device capable of switching a plurality of spool pins between a stored state and a deployed state and a sewing machine having the thread standing device to improve the operability of the switching operation.

In the present invention, a thread standing device of a sewing machine capable of switching a plurality of spool pins between a stored state and a deployed state, the thread standing device including: an operation portion related to a switching operation of the plurality of spool pins, wherein the plurality of spool pins are switched from the stored state to the deployed state when the operation portion is operated.

In the above described thread standing device, it is preferred that the thread standing device further includes a base which swingably supports the spool pins; a slider which is slidably supported by the base; and an elastic body which energizes the spool pins in a direction of switching from the stored state to the deployed state, wherein the slider includes a stopper and an actuating portion which makes the slider

slide when the operation portion is operated, the spool pins include a stored locking portion configured to be engaged with the stopper in the stored state and a deployed locking portion configured to be engaged with the stopper in the deployed state, and the slider is configured to slide for releasing an engagement between the stored locking portion and the stopper and swinging the spool pins kept in the stored state by the elastic body and the deployed locking portion is configured to be engaged with the stopper to keep the spool pins in the deployed state when the operation portion is operated.

In the above described thread standing device, it is preferred that the plurality of spool pins are configured to be simultaneously switched from the stored state to the deployed state when the operation portion is operated.

In the above described thread standing device, it is preferred that the plurality of spool pins are configured to be sequentially switched from the stored state to the deployed state when the operation portion is operated.

20 In addition, the present invention also relates to the sewing machine including any one of the above described thread standing devices.

By using the thread standing device and the sewing machine having the thread standing device of the present invention, a plurality of spool pins is switched from the stored state and the deployed state when the operation portion is operated. Thus, the operability is improved.

BRIEF DESCRIPTION OF THE DRAWINGS

30 FIG. 1 is a perspective view of a sewing machine having the thread standing device in the first embodiment of the present invention and a perspective view showing a stored state and a deployed state of the spool pins in the thread standing device.

35 FIG. 2 is an exploded view of the thread standing device shown in FIG. 1.

FIGS. 3A and 3B are explanation drawings related to operations of the thread standing device shown in FIG. 1.

40 FIGS. 4A and 4B are explanation drawings related operations after FIGS. 3A and 3B.

45 FIGS. 5A to 5C are explanation drawings related operations of the thread standing device in the second embodiment.

DETAILED DESCRIPTION OF THE INVENTION

50 Hereafter, an embodiment of the thread standing device and an embodiment of the sewing machine having the thread standing device of the present invention will be explained with reference to the drawings. In the following explanation, the explanation will be made using the directions of right, left, front, rear, up, down, X, Y and Z shown in the drawings for convenience.

55 FIG. 1 is a drawing schematically showing the first embodiment of the thread standing device of the present invention and an embodiment of the sewing machine on which the thread standing device is mounted. Note that a partially enlarged view of FIG. 1 is related to a thread standing device 1 of the present embodiment showing the stored state where the later described two spool pins (right spool pin 13, left spool pin 14) are pressed down and the deployed state where the right spool pin 13 and the left spool pin 14 are raised up by moving the later described operation lever 10. In addition, a sewing machine 2 of the present embodiment shown in FIG. 1 is switched to a usage state

(the deployed state of the right spool pin 13 and the left spool pin 14) where the sewing can be performed. In the sewing machine 2 of the present embodiment, thread reels 52 around which upper thread 51 is wound are placed on the right spool pin 13 and the left spool pin 14. In addition, the sewing machine 2 includes a threading antenna 53 where a support shaft 53a can be stored in the sewing machine 2 and the upper thread 51 is inserted into needle holes of needles 54 via the threading antenna 53 and other components. In the sewing machine 2 of the present embodiment, the right spool pin 13 and the left spool pin 14 can be switched to the stored state, the support shaft 53a can be stored in the sewing machine 2 and an upper lid 55 can be closed by the later described procedures. Namely, the sewing machine 2 can be downsized and dust and the like can be prevented from entering during the storage.

FIG. 2 is an exploded view of the thread standing device 1. The thread standing device 1 of the present embodiment includes a base plate 3, a right shaft plate 4, a left shaft plate 5, a right slider 6, a left slider 7, a right tension spring 8, a left tension spring 9, an operation lever 10, an operation rod 11, an operation rod coil spring 12, a right spool pin 13, a left spool pin 14, a right-winding coil spring 15 and a left-winding coil spring 16. In addition, these members are mounted by the illustrated screws 31 and E-rings 32. Note that the base plate 3, the right shaft plate 4 and the left shaft plate 5 of the present embodiment correspond to "base" of the present specification. In addition, the right slider 6 and the left slider 7 of the present embodiment correspond to "slider" of the present specification, the operation lever 10 and the operation rod 11 of the present embodiment correspond to "operation portion" of the present specification, the right spool pin 13 and the left spool pin 14 of the present embodiment correspond to "spool pin" of the present specification and the right-winding coil spring 15 and the left-winding coil spring 16 of the present embodiment correspond to "elastic body" of the present specification.

The base plate 3 includes a base plate body 3a, two long holes 3b penetrating through the base plate body 3a and extending in the left-right direction and three slider pins 3c protruded upward from the base plate body 3a. In addition, the base plate 3 includes an operation rod rotating shaft 3d located on the right part of the base plate body 3a so as to be protruded upward and an operation rod stopper 3e located near the operation rod rotating shaft 3d so as to be protruded upward. Although the reference numeral is omitted in FIG. 2, the base plate 3 includes two spring pins protruded downward from the base plate body 3a so that one end portion of the right tension spring 8 and one end portion of the left tension spring 9 are hooked on the spring pins. The base plate 3 of the present embodiment is mounted on the frame of the sewing machine 2 by not illustrated screws.

As illustrated, the right shaft plate 4 and the left shaft plate 5 have the same shape. The right shaft plate 4 and the left shaft plate 5 include shaft plate bodies 4a, 5a having an L-shape and spool pin rotating shafts 4b, 5b protruded rearward from the shaft plate bodies 4a, 5a respectively. As illustrated, the right shaft plate 4 and the left shaft plate 5 are mounted on the base plate 3 by the screws 31.

The right slider 6 includes a right slider body 6a having a plate shape. The right slider body 6a is provided with a right stopper 6b formed by folding the right slider body 6a upward. In addition, the right slider 6 includes two slider pins 6c protruded downward from the right slider body 6a so that the slider pins 6c are inserted into the long holes 3b. After the slider pins 6c are inserted into the long holes 3b, the E-rings 32 are fitted around the slider pins 6c. Thus, the

right slider 6 can be slidably mounted on the base plate 3. In addition, the right slider 6 includes a spring pin 6d protruded downward from the right slider body 6a and a right actuating pin 6e protruded upward from the right slider body 6a.

The left slider 7 includes a left slider body 7a having a plate shape. The length of the left slider body 7a is longer than that of the right slider 6. The left slider body 7a is provided with a left stopper 7b formed by folding the left slider body 7a upward and three long holes 7c extended in the left-right direction so that the slider pins 3c are inserted into the long holes 7c. After the long holes 7c are inserted around the slider pins 3c, the E-rings 32 are fitted around the slider pins 3c. Thus, the left slider 7 can be slidably mounted on the base plate 3. In addition, the left slider 7 includes a spring pin 7d protruded downward from the left slider body 7a and a left actuating pin 7e protruded upward from the left slider body 7a.

Note that the above described right stopper 6b and left stopper 7b correspond to "stopper" of the present specification and the right actuating pin 6e and the left actuating pin 7e correspond to "actuating portion" of the present specification.

One end portion of the right tension spring 8 is hooked on the above described not illustrated spring pin provided on the base plate 3 and the other end portion is hooked on the spring pin 6d of the right slider 6. Consequently, an energizing force is applied to the right slider 6 in the direction directed from right to left (the direction of arrow mark D shown in FIG. 2).

One end portion of the left tension spring 9 is hooked on the above described spring pin provided on the base plate 3 and the other end portion is hooked on the spring pin 7d of the left slider 7. Consequently, an energizing force is applied to the left slider 7 in the direction directed from left to right (the direction of arrow mark B shown in FIG. 2).

The operation lever 10 includes an operation lever body 10a located below and held by the operation rod 11 and a knob portion 10b protruded upward from the operation lever body 10a.

The operation rod 11 includes an operation rod body 11a having a plate shape. The operation rod body 11a is provided with a right pressing portion 11b and a left pressing portion 11c formed by folding the operation rod body 11a upward and a shaft hole 11d so that the operation rod rotating shaft 3d is inserted into the shaft hole 11d.

As illustrated, the above described operation lever 10 is mounted on the operation rod 11 by the screw 31. As illustrated, the operation rod 11 is rotatably mounted on the base plate 3 by inserting the shaft hole 11d around the operation rod rotating shaft 3d while interposing the operation rod coil spring 12 and fitting the E-rings 32 around the operation rod rotating shaft 3d. After the operation rod 11 is mounted, an energizing force is applied to the operation rod 11 by the operation rod coil spring 12 in a clockwise direction in a plan view (the direction of arrow mark A shown in FIG. 2).

The right spool pin 13 includes a right rod-shaped portion 13a having a circular shape in a cross-section of an XZ plane and a right fixing portion 13b provided on one end portion 60 of the right rod-shaped portion 13a. As shown in a partially enlarged view of FIG. 2, the right fixing portion 13b includes a base portion 13c extended in the up-down direction and a protruded portion 13d extended rightward from the base portion 13c (extended in the opposite direction of the right rod-shaped portion 13a) when the right rod-shaped portion 13a is directed in the left-right direction. In the base portion 13c, a right side surface located at an upper portion of the

protruded portion **13d** is referred to as a deployed locking portion **13e**, an upper surface of the protruded portion **13d** is referred to as a deployed stopper portion **13f** and a lower surface of the protruded portion **13d** is referred to as a stored locking portion **13g**. Note that the protruded portion **13d** includes a curved surface having an arc shape at a connection portion between the upper surface and the right side surface of the protruded portion **13d**. In the following explanation, the above described curved surface is referred to as a pushing-out cam **13h**. In addition, the right fixing portion **13b** is provided with a shaft hole **13j** so as to be inserted around the spool pin rotating shaft **4b** of the right shaft plate **4**.

The left spool pin **14** includes a left rod-shaped portion **14a**, a left fixing portion **14b**, a base portion **14c**, a protruded portion **14d**, a deployed locking portion **14e**, a deployed stopper portion **14f**, a stored locking portion **14g**, a pushing-out cam **14h** and a shaft hole **14j** which have the same configurations as those of the above described right spool pin **13**. Note that the left spool pin **14** has the same shape as the right spool pin **13** and the left spool pin **14** is rotated by 180 degrees around the vertical axis when compared to the right spool pin **13**. Namely, although the shapes of the positions of the components forming the left spool pin **14** are same as those of the right spool pin **13**, the explanation will be made by using different reference numerals for convenience.

The right spool pin **13** is rotatably mounted on the right shaft plate **4** by inserting the shaft hole **13j** around the spool pin rotating shaft **4b** while interposing the right-winding coil spring **15** and fitting the E-rings **32** around the spool pin rotating shaft **4b**. After the right spool pin **13** is mounted, an energizing force is applied to the right spool pin **13** by the right-winding coil spring **15** in a clockwise direction in a viewpoint viewed from rear to front (the direction of arrow mark A shown in FIG. 2).

The left spool pin **14** is rotatably mounted on the left shaft plate **5** by inserting the shaft hole **14j** around the spool pin rotating shaft **5b** while interposing the left-winding coil spring **16** and fitting the E-rings **32** around the spool pin rotating shaft **5b**. After the left spool pin **14** is mounted, an energizing force is applied to the left spool pin **14** by the left-winding coil spring **16** in a counter-clockwise direction in a viewpoint viewed from rear to front (the direction of arrow mark C shown in FIG. 2).

The thread standing device **1** composed of the above described components is operated as shown in FIGS. 3A, 3B and FIGS. 4A, 4B. The operation lever **10** is omitted in FIGS. 3A, 3B and FIGS. 4A, 4B for the convenience of explanation.

First, in the state shown in FIG. 3A (stored state), the operation rod **11** is stopped in a state of being pressed against the operation rod stopper **3e** by an energizing force energized by the operation rod coil spring **12** (energizing force of clockwise direction in a plan view).

In the above described state, the right slider **6** is moved leftward by an energizing force of the right tension spring **8** and the right actuating pin **6e** is in contact with the right pressing portion **11b**. In addition, the left slider **7** is moved rightward by an energizing force of the left tension spring **9** (shown in FIG. 2) and the left actuating pin **7e** is in contact with the left pressing portion **11c**.

In the above described state, the stored locking portion **13g** of the right spool pin **13** is pressed against the right stopper **6b** of the right slider **6** and the stored locking portion **14g** of the left spool pin **14** is pressed against the left stopper **7b** of the left slider **7**. Thus, the right spool pin **13** and the

left spool pin **14** are stopped in a horizontally inclined posture (posture where the right rod-shaped portion **13a** and the left rod-shaped portion **14a** are directed in the left-right direction).

5 Note that the rotation angle of the operation rod **11** in the stored state shown in FIG. 3A is referred to as $\theta 0$ and the position of the right actuating pin **6e** and the left actuating pin **7e** in the left-right direction is referred to as $d0$.

FIG. 3B shows the state that an operator operates the 10 operation lever **10** (shown in FIG. 2) to rotate the operation rod **11** in a clockwise direction in a plan view. In FIG. 3B, the operation rod **11** is rotated from the rotation angle $\theta 0$ shown in FIG. 3A to a rotation angle $\theta \alpha$. When the operation rod **11** is rotated, the right pressing portion **11b** presses the 15 right actuating pin **6e** rightward and the left pressing portion **11c** presses the left actuating pin **7e** leftward. Thus, the right slider **6** is slid rightward and the left slider **7** is slid leftward. Note that FIG. 3B shows the state that the right slider **6** and the left slider **7** stopped at the position $d0$ in FIG. 3A are slid 20 to a position $d\alpha$.

As described above, when the right slider **6** and the left slider **7** are slid, the right stopper **6b** is separated from the 25 stored locking portion **13g** and the left stopper **7b** is separated from the stored locking portion **14g**. Therefore, the right spool pin **13** is rotated in a clockwise direction in a viewpoint viewed from rear to front by an energizing force of the right-winding coil spring **15** and the left spool pin **14** is rotated in a counter-clockwise direction in a viewpoint viewed from rear to front by an energizing force of the 30 left-winding coil spring **16**.

When the right spool pin **13** is rotated in a clockwise direction, the deployed locking portion **13e** is in contact with the right stopper **6b** as shown in FIG. 4A. Therefore, the right spool pin **13** is stopped in a posture raised upward. In 35 addition, when the left spool pin **14** is rotated in a counter-clockwise direction, the deployed locking portion **14e** is in contact with the left stopper **7b**. Thus, the left spool pin **14** is stopped in a posture raised upward. As described above, in the thread standing device **1** of the present embodiment, the right spool pin **13** and the left spool pin **14** in the stored state shown in FIG. 3A can be switched to the deployed state 40 shown in FIG. 4A by operating the operation lever **10**.

When the operator releases a hand from the operation lever **10**, the operation rod **11** is rotated in a clockwise 45 direction in a plan view as shown in FIG. 4A until the operation rod **11** is pressed against the operation rod stopper **3e** or until the right stopper **6b** is in contact with the deployed stopper portion **13f** or until the left stopper **7b** is in contact with the deployed stopper portion **14f** by the operation 50 rod coil spring **12**. Even when the operation rod **11** is rotated, the deployed locking portion **13e** is still in contact with the right stopper **6b** and the deployed locking portion **14e** is still in contact with the left stopper **7b**. Thus, the right spool pin **13** and the left spool pin **14** are kept in the 55 deployed state.

FIG. 4B shows the middle state of switching the right spool pin **13** and the left spool pin **14** from the deployed state to the stored state. When the operator presses down the right spool pin **13** in the direction of the illustrated arrow marks 60 (counter-clockwise direction in a viewpoint viewed from rear to front), the right fixing portion **13b** presses the right stopper **6b** to slide the right slider **6** rightward. When the right spool pin **13** is further rotated to the horizontally inclined posture shown in FIG. 3A, the state of pressing the right stopper **6b** by the right fixing portion **13b** is released 65 and the right slider **6** is moved leftward by an energizing force of the right tension spring **8**. Thus, the right stopper **6b**

and the stored locking portion $13g$ are engaged with each other and the right spool pin 13 is kept in the stored state. In the present embodiment, since the pushing-out cam $13h$ having a curved surface is provided on a corner portion of the stored locking portion $13g$, a sliding amount of the right slider 6 when the stored locking portion $13g$ is rotated to press the right stopper $6b$ is smaller compared to the case where the pushing-out cam $13h$ is not provided. Namely, since an amount of deflection of extending the right tension spring 8 is smaller when the right slider 6 is slid rightward, a force required for pressing down the right spool pin 13 is smaller.

The left spool pin 14 in the deployed state can be also switched to the stored state same as the right spool pin 13 . Note that the right slider 6 and the left slider 7 of the present embodiment are independently operated when switched from the deployed state to the stored state. Accordingly, when switching the right spool pin 13 and the left spool pin 14 from the deployed state to the stored state, it is possible to press down the right spool pin 13 and the left spool pin 14 simultaneously or press down one of them to switch it to the stored state and then press down the other.

Next, the second embodiment of the thread standing device of the present invention will be explained with reference to FIGS. 5A to 5C. In the following explanation, the difference from the above described thread standing device 1 will be explained and the explanation of the common configurations will be omitted by adding the same reference numerals in FIGS. 5A to 5C. In addition, since the operation of switching from the deployed state to the stored state of the above thread standing device 1 shown in FIG. 4B is same as that of a thread standing device $1B$ of the present embodiment, the operation from the stored state to the deployed state will be explained below.

The thread standing device $1B$ includes a right slider $6B$ instead of the above described right slider 6 provided on the thread standing device 1 . The right slider $6B$ is different from the right slider 6 in the position of the right actuating pin $6e$ with respect to the right slider body $6a$.

The right spool pin 13 and the left spool pin 14 provided on the thread standing device $1B$ is stopped in a horizontally inclined posture in the stored state shown in FIG. 5A. In the stored state, the operation rod 11 and the left slider 7 of the thread standing device $1B$ of the present embodiment are located at the same position as the operation rod 11 and the left slider 7 of the above described thread standing device 1 . Namely, the rotation angle $\theta 0$ of the operation rod 11 of the thread standing device $1B$ in the stored state and the position $d0$ of the left actuating pin $7e$ provided on the left slider 7 in the left-right direction are same as the rotation angle of the operation rod 11 and the position of the left actuating pin $7e$ in the left-right direction shown in FIG. 3A respectively. On the other hand, the right actuating pin $6e$ of the right slider $6B$ of the present embodiment is provided at the position separated rightward from the right pressing portion $11b$ by a distance 6 in the stored state shown in FIG. 5A. Note that the distance 6 is approximately same as the distance from the position $d0$ to the position da shown in FIG. 3B.

Also in the thread standing device $1B$ of the present embodiment, when switching from the stored state to the deployed state, the operator operates the operation lever 10 (shown in FIG. 2) to rotate the operation rod 11 in a counter-clockwise direction in a plan view shown in FIG. 5B. When the operation rod 11 is rotated from the rotation angle $\theta 0$ shown in FIG. 5A to the rotation angle $\theta \alpha$ shown in FIG. 5B, the left pressing portion $11c$ is moved leftward to press the left actuating pin $7e$ from the position $d0$ to the

position da . Thus, the left slider 7 is slid leftward. Accordingly, after the left spool pin 14 is rotated by an energizing force of the left-winding coil spring 16 , the left spool pin 14 is kept in the deployed state shown in FIG. 5B.

In a state that the operation rod 11 is rotated to the rotation angle $\theta \alpha$, the right pressing portion $11b$ is moved rightward. Here, since the right pressing portion $11b$ and the right actuating pin $6e$ are originally separated from each other by the distance 6 which is approximately same distance between the position $d0$ to the position da , the right pressing portion $11b$ is moved so as to be approximately in contact with the right actuating pin $6e$ as shown in FIG. 5B. Thus, the right spool pin 13 is stopped still in the stored state.

When the operator releases a hand from the operation lever 10 in this state, the operation rod 11 and the right slider 6 operated as shown in FIG. 5B are moved to the position of FIG. 5A while the left spool pin 14 is still the deployed state. Namely, when the operation lever 10 is rotated to the rotation angle $\theta \alpha$, only the left spool pin 14 can be switched from the stored state to the deployed state while the right spool pin 13 is still the stored state.

On the other hand, in order to switch both the right spool pin 13 and the left spool pin 14 to the deployed state, the operation rod 11 is rotated to a rotation angle $\theta \beta$ as shown in FIG. 5C. Note that the rotation angle $\theta \beta$ is larger than the rotation angle $\theta \alpha$. Although the right pressing portion $11b$ is moved so as to be approximately in contact with the right actuating pin $6e$ in a state that the operation rod 11 is rotated to the rotation angle $\theta \alpha$, the right actuating pin $6e$ which is located at the position $d0$ in the left-right direction in the stored state as shown in FIG. 5A can be moved to the position da by rotating the operation rod 11 to the rotation angle $\theta \beta$ in the present embodiment. Namely, since the right slider 6 is slid rightward and the right stopper $6b$ is separated from the stored locking portion $13g$, the right spool pin 13 is rotated by an energizing force of the right-winding coil spring 15 and switched to the deployed state shown in FIG. 5C. When the operation rod 11 is rotated to the rotation angle $\theta \alpha$, the left actuating pin $7e$ pressed by the left pressing portion $11c$ is moved to the position $d\beta$ which is more separated from the position $d0$ than the position da . Namely, as shown in FIG. 5C, the left stopper $7b$ in this state is further moved leftward compared to the position shown in FIG. 5B. However, since the length of the deployed locking portion $14e$ is sufficiently ensured in the present embodiment, the left stopper $7b$ is in contact with the deployed locking portion $14e$ and the deployed state is kept even in the state shown in FIG. 5C.

As described above, in the thread standing device $1B$, the right spool pin 13 and the left spool pin 14 can be sequentially switched from the stored state to the deployed state in accordance with an operation amount of the operation lever 10 . Namely, the operator can select the number of the spool pins of the deployed state in accordance with the sewing operation of the sewing machine. Thus, the operability can be improved and the usability can be improved.

Although the embodiments realizing the present invention are exemplified above, the present invention is not limited to a specific embodiment. Unless particularly limited in the above described explanation, various modification and change are possible in the range of the scope of the present invention described in the claims. In addition, the above described effects of the embodiments merely exemplify the effects arisen from the present invention. The effects of the present invention are not limited to the above described effects.

For example, the thread standing device 1B shown in FIGS. 5A to 5C is configured so that the left spool pin 14 is switched to the deployed state and then the right spool pin 13 is switched to the deployed state in accordance with the operation amount of the operation lever 10. However, the order of switching to the deployed state can be reversed.

In addition, the number of the spool pins to be switched from the stored state to the deployed state is two in the above described embodiment. However, it is also possible to switch three or more spool pins from the stored state to the deployed state by adding a new slider in addition to the right slider 6 and the left slider 7 and a new pressing portion in addition to the right pressing portion 11b and the left pressing portion 11c provided on the operation rod 11, for example.

Note that, this invention is not limited to the above-mentioned embodiments. Although it is to those skilled in the art, the following are disclosed as the one embodiment of this invention.

Mutually substitutable members, configurations, etc. disclosed in the embodiment can be used with their combination altered appropriately.

Although not disclosed in the embodiment, members, configurations, etc. that belong to the known technology and can be substituted with the members, the configurations, etc. disclosed in the embodiment can be appropriately substituted or are used by altering their combination.

Although not disclosed in the embodiment, members, configurations, etc. that those skilled in the art can consider as substitutions of the members, the configurations, etc. disclosed in the embodiment are substituted with the above mentioned appropriately or are used by altering its combination.

While the invention has been particularly shown and described with respect to preferred embodiments thereof, it should be understood by those skilled in the art that the foregoing and other changes in form and detail may be made therein without departing from the spirit and scope of the invention as defined in the appended claims.

What is claimed is:

1. A thread standing device of a sewing machine capable of switching a plurality of spool pins between a stored state and a deployed state, the thread standing device comprising:
  - 5 an operation portion configured to be moved for switching the plurality of spool pins;
  - a base which swingably supports the plurality of spool pins;
  - a plurality of sliders which is slidably supported by the base; and
  - 10 an elastic body which energizes the plurality of spool pins in a direction of switching from the stored state to the deployed state, wherein
  - 15 each of the plurality of sliders includes a stopper configured to keep each of the spool pins in the stored state, each of the plurality of spool pins includes a stored locking portion configured to be engaged with the stopper in the stored state,
  - 20 when the operation portion is moved, the stopper is slid from a state of being engaged with the stored locking portion to a state being separated from the stored locking portion for switching all of the plurality of spool pins from the stored state to the deployed state by an energizing force of the elastic body.
  - 25 2. The thread standing device according to claim 1, wherein
  - when the operation portion is moved, the plurality of spool pins are configured to be simultaneously switched from the stored state to the deployed state.
  - 30 3. The thread standing device according to claim 1, wherein
  - when the operation portion is moved, the plurality of spool pins are configured to be sequentially switched from the stored state to the deployed state.
  - 35 4. A sewing machine including the thread standing device of claim 1.
